(57) **CLAIM**

(**) Term: **14 Years**

The ornamental design for a ladder climbing demonstration exhibit, as shown and described.

(21) Appl. No.: **29/335,476**

DESCRIPTION

(22) Filed: **Apr. 16, 2009**

FIG. 1 is a perspective view of a ladder climbing demonstration exhibit showing our design;

(51) **LOC (9) Cl.** **19-07**

FIG. 2 is a side perspective view thereof;

(52) **U.S. Cl.** **D19/62**

FIG. 3 is a top view thereof;

(58) **Field of Classification Search** D19/62,

FIG. 4 is an end view thereof;

D19/100; D25/62, 64, 65, 68, 69; 248/210;

182/93, 106, 115–126, 196, 207

See application file for complete search history.

FIG. 5 is a perspective view of an alternate second embodiment of the ladder climbing demonstration exhibit showing our design;

(56) **References Cited**

FIG. 6 is a side perspective view of the alternate second embodiment of the ladder climbing demonstration exhibit, the opposite side view being a mirror image thereof;
